UNITED STATES PATENT OFFICE.

JESSE M. NICHOLS, OF ANSLEY, NEBRASKA.

GRINDING-MILL.

SPECIFICATION forming part of Letters Patent No. 449,229, dated March 31, 1891.

Application filed December 12, 1890. Serial No. 374,488. (No model.)

To all whom it may concern:

Be it known that I, JESSE M. NICHOLS, a citizen of the United States, residing at Ansley, in the county of Custer and State of Nebraska, have invented certain new and useful Improvements in Grinding-Mills; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to mills and mechanism for transmitting motion to the burr and starting and stopping the same according as the speed of the power-transmitting mechanism exceeds or falls short of the predetermined speed for which the said power-transmitting mechanism is regulated.

20 The object of the invention is to provide a mill which will be automatic in its action and which will start easily and stop when the power falls below the normal, thereby preventing the choking of the burrs.

25 Another object of the invention is to prevent damage to the burrs in the event of a foreign hard substance coming between them.

30 The improvements consist in the novel features and the peculiar construction and combination of parts, which will be hereinafter more fully described and claimed, and which are shown in the accompanying drawings, in

35 which—

Figure 1 is a perspective view of a mill and power-transmitting mechanism embodying my improvements. Fig. 2 is a plan view showing the mill and the mechanism for regulating the degree of fineness of the grinding. Fig. 3 is a detail vertical section of the mill on a larger scale. Fig. 4 is a detail view of the mill-spindle, showing the spiral ribs thereon.

40 The bed or frame A is oblong in form, being preferably of metal and of suitable size to support the mill and the power-transmitting and governor mechanism. The walking beam B is pivoted between its ends to the top of the standard A', and is weighted at one end to counterbalance the connections, and its other end is connected by pitmen b b with

the levers b' b', which are mounted on the shaft C, on which is keyed the ratchet-wheel b³ and the gear-wheel D. The levers b' b' extend in opposite directions and are provided near their movable ends with the pawls b² b², which alternately act on the ratchet-wheel b³ to impart a continuous rotary motion thereto and to the shaft C, in the well-known manner. The gear-wheel D meshes with the pinion e on the shaft E, on which is mounted the band-pulley F and the balance-wheel f, the band-pulley being connected by the endless band g with the band-pulley h on the shaft H, on the other end of which the spiral ribs i are formed, and on which the burr J is secured. The end of the shaft H passes through the hopper K, to which is secured the burr L. The shaft H is provided with the balance-wheel h' and the friction-wheel 12, and is adapted to move endwise in its bearings to regulate the space between the burrs J and L. The coupling m at the end of the shaft H opposite to the burr J is connected with the lever M by a break-pin m', and the lever M is connected with an arm projected from the frame A by a break-pin m², the break-pins being preferably of wood. The free end of the lever M is acted on by the set-screw N to move the shaft H in its bearings to regulate the distance between the burrs I and L. The break-pins m' and m² possess a certain amount of elasticity, which facilitates the process of grinding, and in the event of a hard substance coming between the burrs one or the other, or possibly both, of the pins m' and m², will break and permit the burrs to separate a sufficient distance to prevent injury thereto. The shaft O is journaled in the standards at the end of the frame A, and is provided at its end with the feed-wheel P, which is located in the hopper K, and with the friction-wheel o. The slide k is adjustable in the hopper K to regulate the feed of the grain.

45 The governor for starting and stopping the feed of the grain is composed of the bracket 6, which is bolted to the frame A, the vertical shaft 4, having the bevel-wheel 3, which meshes with a corresponding bevel-wheel 2 on the shaft E, the governor-balls connected with the shaft 4 and rotated therefrom, the sleeve Q, adapted to slide on the shaft 4, the

rod 7, having a loose connection with the sleeve Q, and threaded at its lower end, on which are mounted two set-nuts q, the lever 8, pivoted at 9 to the frame A, and having its end held to the rod 7 between the nuts q, and having its other end bent to extend beneath the frame A and thence upward, and provided with the idle-wheel 11, which is adapted to be thrust against the friction-wheels 12 and 10 o and transmit motion from the shaft H to the shaft O.

In practice the mill is to be operated from any light motive power, preferably by a wind-mill, which is connected with the walking-beam B. By regulating the connection between the lever 8 and the rod 7, which is effected by the nuts q, the governor can be adjusted to throw the feed mechanism in gear at any rate of speed of the power-transmitting mechanism. The power-transmitting mechanism being set in motion, the shaft H will be rotated by the instrumentalities hereinbefore described, and will operate the burr J and grind the grain. When the required speed has been obtained, the wheel 11 will be forced against the wheels 12 and o and throw the feed mechanism in gear. Should the speed fall below that for which the governor is adjusted, the wheel 11 will be withdrawn from contact with the wheels 12 and o and the feed mechanism will be thrown out of gear.

For cracking grain simply, the burr J is removed, and the spiral ribs I, in connection with the hopper, will effect the desired result.

Having thus described my invention, what I claim to be new, and desire to secure by Letters Patent, is—

1. The combination, with the mill, mechanism for operating the mill, and the shaft O, 40 having the feed-wheel P, of a governor in gear with the mill-operating mechanism, the rod 7 on the governor-shaft, and the adjustable lever 8 and its wheel 11, adapted to automatically throw the feed mechanism in 45 and out of gear with the mill-operating mechanism, substantially as described, and for the purpose specified.

2. The combination, with the mill and the feed mechanism, including the friction-wheels 50 12 and o, of the governor in gear with the mill-operating mechanism, the rod 7, the lever 8, means for adjustably connecting one end of the lever with the rod 7, and the wheel 11 on the other end of the lever and adapted to 55 bear against the wheels 12 and o to connect the feed mechanism with the mill-operating mechanism, substantially as described.

3. In combination, the hopper, the shaft H, the burrs J and L, the shaft E in gear with 60 the shaft H, having the wheel 12, the shaft O, having the wheel o and the feed-wheel P, the governor in mesh with the shaft E, the rod 7, the lever 8 adjustably connected with the rod 7, and the wheel 11 on the free end of the lever 8 and adapted to be brought into contact with the wheels 12 and o, substantially as 65 shown and described, and for the purpose specified.

In testimony whereof I affix my signature in 70 presence of two witnesses.

JESSE M. NICHOLS.
